SPRINKLER BASE

Jerry R. Hayes, Peoria, Ill., assignor to L. R. Nelson Mfg.
Co., Inc., Peoria, Ill., a corporation of Illinois

Filed May 24, 1965, Ser. No. 85,426

Term of patent 14 years

(Cl. D91—1)

Fig. 1.

Fig. 2.

Fig. 3.

Fig. 4.

Fig. 5.

FIGURE 1 is a perspective view of a sprinkler base showing my design;

FIGURE 2 is a side elevational view of the sprinkler base;

FIGURE 3 is a rear elevational view of the sprinkler base;

FIGURE 4 is a top plan view of the sprinkler base; and

FIGURE 5 is a front elevational view of the sprinkler base.

I claim:

The ornamental design for a sprinkler base, substantially as shown.
